US0D1088317S

(12) **United States Design Patent** (10) **Patent No.:** **US D1,088,317 S**
(45) **Date of Patent:** **** Aug. 12, 2025**

(54) **LIGHTING FIXTURE HAVING STRUTS**

(71) Applicant: **HLI SOLUTIONS INC.**, Greenville, SC (US)

(72) Inventor: **Robert R. Nankil**, Buena Park, CA (US)

(73) Assignee: **HLI SOLUTIONS, INC.**, Greenville, SC (US)

(**) Term: **15 Years**

(21) Appl. No.: **29/793,289**

(22) Filed: **May 17, 2022**

(57) **CLAIM**

The ornamental design for a lighting fixture having struts, as shown and described.

DESCRIPTION

FIG. 1 is a top plan view of a lighting fixture having struts; FIG. 2 is a top perspective view of the lighting fixture illustrated in FIG. 1;

FIG. 3 is a front elevational view of the lighting fixture illustrated in FIGS. 1 and 2;

FIG. 4 is a left side elevational view of the lighting fixture illustrated in FIGS. 1-3, the right side being the mirror image thereof;

FIG. 5 is a bottom plan view of the lighting fixture illustrated in FIGS. 1-4; and,

FIG. 6 is a bottom perspective view of the lighting fixture illustrated in FIGS. 1-5.

The broken lines in the drawings illustrate portions of the lighting fixture having struts that form no part of the claimed design.

1 Claim, 3 Drawing Sheets
